Inventor:
S. Davis, Jr.

Shadrack Davis, Junr. of Dartmouth, Mass.
Letters Patent

The schedule referred to in these Letters Patent and making part of the same containing a description in the words of the said Shadrack Davis, himself of his improvement in the machine for removing stones, &c.

To all to whom these presents shall come, Be it known that I Shadrack Davis, Junr. of Dartmouth in the County of Bristol and State of Massachusetts, have invented a new and useful improvement in a machine for removing earth, stones &c and that the following is a full and exact description of the construction of the said machine as invented or improved by me, and machine may be operated by horse, or steam power. Drawing Fig. 1. A is an axle. R P are wheel
or rollers. XXXX, are caps over the ends of said wheels, and secured with bolts thru the frame. B B. is the frame and rollers lay in. M is a post with a crook at top. B B. are braces, securing the post and frame. H. is the shaft or tongue to the carriage. B. B. are shafts fastened one end in the frame and the other end to the straps, on the carriage, may be seen at O. O. in Fig 2nd with a joint in them near the frame. N is the scraper. I I are chains one end fastened to the roller and the other ends secured to the scraper at O. O. C C are chains fastened to the back board of the said scraper, and pass over roller P and fasten to roller R. on the under side. T T are chains fastened to R and the scraper carriage. S is a lever in R. O is a wheel with a spoke secured to it, and to the lever with a nut and nut and bolt and pole. Fig 2. A is the body of the scraper or drag. P are points or shears with a cutlass in them. O O are straps. B B are braces of shafts. S is a wicket. Fig 3. A is a board in the back part of the scraper to prevent the load from discharging. B is a bolt secured in post on the upper edge. N N N N are straps, fastened to the board and secure the bolt to the side of the board. M M are staples fastened to the board to secure the chain C C. in Fig 1. O is a screw fastened to the bolt. R is a lever one end bowed

Drawing

To the edge of the board and goes thru the scraper. It are springs fastened to the bottom of the scraper, and pass between the board and the bolt and secure the bolt across the board. It is a socket to receive the handspike to assist in loading. Fig 4th is a handspike. Fig 5th is a wheel. Fig 6th is a spring fastened to the after part of the scraper fastening the back board of the scraper and the scraper screws the bolt of the bolt together. Fig 7th is a point or shear with a cutter in it.

The above machine is calculated to move earth, stone &c. and may be used in the following form. The power applied to the tongue, the iron thrown forward into the crotch will set the scraper to the ground then by raising the after part of the after part of the scraper will direct the points of said scraper into the ground. The carriage moving ahead will carry them under the earth or intended load the iron brought back will raise the load. Now by ungearing the bolt in the back board from the springs that are attached to the bottom of the scraper will fall the back part of said scraper will discharge the load, for moving heavy stones may be hoisted and discharged in the same manner.

The above named points or shear, I contemplate using on scraper, not having one wheel, for moving short distances.

The improvement I claim is, not the whole machine described, but claim the points or shear, with cutter in the fore part of them & the application of said scraper to wheels, and form of hanging it together with applying said points to scraper drawn without wheelz.
